DESIGN FOR A STRINGED MUSICAL INSTRUMENT

Julius W. Knopp, Toledo, Ohio

Application May 16, 1938, Serial No. 77,214

Term of patent 14 years

To all whom it may concern:

Be it known that I, Julius W. Knopp, a citizen of the United States and resident of Toledo, in the county of Lucas and State of Ohio, have invented a new, original, and ornamental Design for a Stringed Musical Instrument, of which the following is a specification, reference being had to the accompanying drawing forming a part thereof.

Figure 1 is a side view of a stringed musical

instrument showing my new design, and Fig. 2 is a top view thereof.

The dominant feature of my design resides in the shaded portion of the neck of the instrument as shown.

I claim:

The ornamental design for a stringed musical instrument, substantially as shown and described.

JULIUS W. KNOPP.
